UNITED STATES PATENT OFFICE

JOHN A. MORTHLAND, OF FOREST PARK, ILLINOIS

SUPPORTING BRACKET

Application filed October 12, 1927. Serial No. 225,704.

My invention relates, more particularly, to supporting brackets for application to faucets of sinks to present supports for articles used about sinks, and particularly strainer receptacles for receiving kitchen waste; my primary object being to provide a novel, simple, inexpensive and sanitary construction of supporting bracket of the general character above referred to, which may be readily positioned for use upon the faucet of a sink.

Referring to the accompanying drawing:

Figure 1 is a front view of the upper portion of a sink structure the faucet of which is equipped with my improved supporting bracket shown as supporting a strainer receptacle. Figure 2 is a plan view of the structure shown in Fig. 1, the wall adjacent the sink being shown in section. Figure 3 is an enlarged sectional view taken at the line 3 on Fig. 2 and viewed in the direction of the arrow, the ends of the laterally extending arms of the bracket being broken away. Figure 4 is a broken sectional view taken at the irregular line 4—4 on Fig. 3 and viewed in the direction of the arrows. Figure 5 is a bottom plan view of the bracket structure shown in Fig. 3; and Figure 6, an enlarged, broken, sectional view taken at the line 6 on Fig. 2 and viewed in the direction of the arrow.

My improved supporting bracket, in its preferred form, comprises a yoke member 7 adapted to straddle the faucet to which it is to be applied at a sink, such as the faucet represented at 8, and a cross rod 9 carried by the yoke member 7 and extending laterally therefrom generally parallel with the splash-board portion 10 of the sink and preferably closely adjacent thereto to serve as a support for one or more articles, such as for example a strainer receptacle represented at 11.

The rod 9, which is preferably bent upwardly at its opposite ends as represented at 12, is preferably longitudinally adjustable in the yoke member 7 to permit this rod to be adjusted to a position in which it extends wholly to one side or the other of the faucet equipped with the bracket device, or equidistantly, or otherwise, at both sides of the faucet.

set, the yoke member 7 being provided with a set screw 13 for holding the rod 9 in adjusted position.

The yoke member 7 presents the downwardly extending arms 14 on which the means for securing the yoke member to the faucet, are mounted, these means being shown in the form of set screws 15 which are threaded in these arms and preferably converge upwardly as shown to a position in which they engage the side wall of the horizontal portion of the faucet 8, at a point below the horizontal axis of the faucet, thereby operating to firmly draw the yoke member 7 into straddling engagement with the faucet.

It is desirable that the bracket structure extend as close as possible to the splash-board 10 while maintaining sufficient clearance between the rod 9 and the splash-board to permit of the applying to the rod 9 of the article, or articles, to be supported thereby. As most faucet structures at the portions thereof adjacent the splash-board 10 are provided with flange portions represented at 16 and flat-wise bearing against the splash-board 10, with their outer faces flaring as represented at 17, and with a bead portion 18, shown as of hexagonal form and spaced forwardly from the flange portion 16, the yoke member 7 is preferably made of such thickness that in applying it to the faucet as shown in the drawings it will rest on the bead portion 18 and be in engagement at its rear edge with the tapered surface 17. The screws 15 are shown as positioned to engage with the faucet between the flanges 16 and 18, though it will be understood that these screws may engage another portion of the faucet if desired.

To ensure the proper seating of the yoke member 7 at its forward edge upon the flange member 18 and at the same time provide the yoke member of such form at its rear edge where it engages the flange 16 that it will set as close as possible to the splash-board 10 as above explained, the yoke member at its front portion is provided with a lug 19 at which it bears against the flange 18 and at its rear edge portion is formed to present the relieved portion 20, it being observed that by relieving the yoke member at the

surface 20 as shown this member will positively seat upon the flange member 18 at a lesser distance from the splash-board 10 than if the underside of this yoke member were 5 perfectly flat, due to the fact that the yoke member engages at its rear edge with a tapering surface 17 of the faucet at a higher point thereon, than in the case of a construction not having the relieved portion referred to.

10 It will be understood that the bracket structure thus provided is adapted for application to faucets of the many different designs commonly provided at sink structures, and when applied to position the article-supporting portion, or portions, thereof extend 15 into the desired close proximity to the splash-board 10.

A bracket structure positioned on a faucet as stated is thus adapted to support articles 20 used about the sink, in close proximity to the splash-board 10 which is not only of advantage in that it avoids such articles extending outwardly over the sink basin to such a distance that they present obstruction to 25 the one working about the sink, but also because articles, such as strainer receptacles which when in supported position bear at their lower edges against the splash-board, may be supported on the bracket in the desired 30 approximately upright position. In the drawings, such a strainer device is shown and comprises a stiff wire bow member 21, the ends of the latter, represented at 22, being bent downwardly as represented at 23 to engage over the bar 9. The bar 9 being in close 35 proximity to the splash-board 10, the receptacle 11 engaging at its lower edge with the splash-board 10, extends in the desired substantially vertical position.

40 While I have illustrated and described a particular construction embodying my invention, I do not wish to be understood as intending to limit it thereto as the same may be variously modified and altered without departing 45 from the spirit of my invention.

What I claim as new, and desire to secure by Letters Patent, is:

1. A supporting bracket for application to 50 a faucet formed of a yoke portion at which the bracket is adapted to straddle the horizontal pipe portion of a faucet, and an arm portion extending laterally from said yoke portion, and upwardly converging set screws engaging the legs of said yoke portion in 55 position to engage the faucet and draw the cross-bar-portion of said yoke-portion against the faucet for securing said yoke portion to said faucet, the engagement of said cross-bar-portion and said screws with said faucet affording a three-point contact.

2. A supporting bracket for application to 60 a faucet formed of a yoke portion at which the bracket is adapted to straddle the horizontal pipe portion of a faucet, the rear edge portion of said yoke portion, at its underside,

inclinining upwardly and rearwardly and the front edge portion thereof presenting a substantially flat bearing surface adapted to bear down on the faucet, an arm portion extending laterally from said yoke portion, and means for securing said bracket at its yoke portion to the faucet. 70

3. A supporting bracket for application to a faucet formed of a yoke-portion having depending spaced apart legs at which the 75 bracket is adapted to straddle the horizontal pipe portion of a faucet, an arm disposed exteriorly of the space between said legs and extending laterally from said yoke-portion and at an angle to said legs, and means movable relative to said yoke-portion and adapted to engage the faucet straddled by said yoke-portion for securing said bracket at its yoke-portion to the faucet. 80

4. A supporting bracket for application to 85 a faucet formed of a yoke-portion having depending spaced apart legs at which the bracket is adapted to straddle the horizontal pipe portion of a faucet, an arm disposed exteriorly of the space between said legs and 90 extending laterally from said yoke-portion and at an angle to said legs and adjustable lengthwise in said yoke-portion, and means movable relative to said yoke-portion and adapted to engage the faucet straddled by 95 said yoke-portion for securing said bracket at its yoke-portion to the faucet.

5. A supporting bracket for application to a faucet formed of a yoke-portion having depending spaced apart legs at which the bracket is adapted to straddle the horizontal pipe portion of a faucet and seat at its cross-bar portion upon said faucet, an arm mounted in the upper part of said yoke-portion and 100 extending laterally therefrom substantially horizontally and adjustable lengthwise in said yoke-portion, and upwardly converging set screws engaging the legs of said yoke-portion in position to engage the faucet below the center of said pipe portion, said set screws 105 operating to draw the cross-bar portion of said yoke-portion down against the faucet, the engagement of said cross-bar portion and said screws with said faucet affording a three-point contact. 110

6. A supporting bracket for application to a faucet formed of a yoke-portion having a cross piece and spaced apart legs depending therefrom at which the bracket is adapted to 115 straddle the horizontal pipe portion of a faucet, an arm mounted on the cross piece of said yoke portion and extending laterally and at an angle to said legs, and means movable relative to said yoke portion and adapted to engage the faucet straddled by said yoke portion for securing said bracket at its yoke portion to the faucet. 120

7. A supporting bracket for application to a faucet formed of a yoke-portion having a 125

cross piece and spaced apart legs depending therefrom at which the bracket is adapted to straddle the horizontal pipe portion of a faucet, a rod in the cross piece of said yoke portion and extending laterally at its opposite ends beyond said yoke portion and at an angle to said legs, said rod being lengthwise adjustable in said yoke portion, and means movable relative to said yoke portion and adapted to engage the faucet straddles by said yoke portion for securing said bracket at its yoke portion to the faucet.
